UNITED STATES PATENT OFFICE.

STEPHEN PETERS, OF OMAHA, NEBRASKA.

COMBINATION TOOL.

Application filed February 3, 1927. Serial No. 165,631.

My invention relates to tools having separable members which are selectively adjustable in different positions so as to form alternatively a plurality of different tools for various purposes. It is the main object of the invention to utilize in a single tool and in a convenient and advantageous manner the elements of a plurality of different tools designed for cognate or commonly associated uses, and in particular to adapt the separable parts of a hand wrench of special construction to be arranged and united so as to form either a screw-driver, a square, or a saw frame, as may be needed. It is a further and incidental object of the invention to make the jaws of an alligator wrench adjustable and also replaceable by substitute jaws, to render one of the members of the wrench available as a measuring rule, and in general to attain all the advantages which are hereinafter described. To accomplish these objects I incorporate in my improved combination tool, as parts thereof, a tubular casing, a tubular handle, a pair of co-acting jaws, a screwdriver blade, and means for uniting these elements in different positions of mutual adjustment.

In said drawings, illustrating the best manner in which I have contemplated applying the principles of the invention, Fig. 1 is a plan view of a wrench which is constructed in accordance with these principles, together with a saw blade and a clamp, which are removably attached thereto; Fig. 2 is a vertical longitudinal section on the section line 2—2 in Fig. 1; Fig. 3 is a sectional plan of a portion of Fig. 1, with parts removed and with the jaws adjusted in alternative positions; Figs. 4 and 5 are perspective details respectively of two separable parts of Fig. 1; Fig. 6 is a plan of parts of Fig. 1 united to form a screw-driver; Fig. 7 is a like view of the same parts united to form a square; Fig. 8 is a similar view of all parts of Fig. 1 united as a hacksaw; and Fig. 9 is a detailed sectional plan of a portion of Fig. 8 with parts removed to show internal arrangement and construction.

In the illustrated specimen of my invention, the casing 1 is in general straight, tubular, rectangular, and of uniform cross-section. It has, extending through one end of it, a pair of removable pivot pins or screws 2; and near the same end an external pivot 5. Through its upper face it has a pinhole 6, as well as a larger and angular hole 7,

which communicates with its hollow interior.

The alligator wrench jaws 8 and 9 have pivot holes 3 and 4 through their rearward ends, and are thereby pivoted in the casing on the removable screw pivots 2. When worn or broken, they may be removed, and new jaws may be substituted for them on the same pivots. They have also on their rearward ends the cogs or teeth 10, 11, 12, and 13, which are best shown in Fig. 9.

The handle 14 is in general straight, tubular and rectangular, like the casing 1. It has the same external width and thickness as does this casing, and a similar cross-sectional area internally. Its forward end is perforated transversely by the hole or socket 15, and its rearward end is closed.

The screwdriver blade 16 has the general form of a straight flat bar. It has the chisel-shaped ends 17 and 18, of unequal size or sharpness, and carries on one side the markings of a graduated scale 19. Midway of its width it is punctured in the direction of its thickness by a plurality of spaced pinholes 26 and 39 for the accommodation of the stop pins 25 and 27, which are herein-after mentioned.

The means that I employ for adjusting and uniting the several parts of the tool in the alternative positions shown, include the metallic block, or plug, which is shown separately in Fig. 5, consisting of a rectangular body portion 20, a finger piece or handle 21, and a neck 22 connecting the body portion with the handle. The body portion 20 is adapted to be inserted through the opening 7 into the close-fitting interior of the casing in the alternative positions shown, and there engages the terminal cogs of the jaws 8 and 9 in the alternative positions indicated in Figs. 3 and 9. In each of these positions, as may be desired, the block is fastened immovably by manipulation of the spring latch 23, which is movable edgewise on its pivot 5, has a tapering recess 24 to hug the neck 22, and is provided with a stop plug or pin 25 elastically predisposed to enter and stay in the pinhole 6 when alined therewith.

To fasten the blade 16 in the close-fitting handle 14 in the alternative positions shown in Figs. 2, 6, 7 and 8, the handle is provided with a stop pin 27, which is adapted to occupy for this purpose the pinholes 26 and 26 alternatively. This projecting pin

is carried by a flat spring 28 which is adjustably pivoted to the handle on a pin 29. When fastened in the handle 14 and the casting 1, as in Fig. 2, this blade reinforces and unites them.

The additional means that I employ for adjusting and uniting the parts of the hacksaw shown in Fig. 8, consist mainly of the clamp which is shown separately in Fig. 4. 10 This clamp comprises the internally rectangular frame or collar 30, and the clamping screw 31, which is rotatable in the collar by means of the finger-piece 32. This collar is slidingly adjustable on the handle 14, as 15 shown in Figs. 1, 2, and 8. It is provided with transversely projecting terminal lugs 33, 33, and 34, for engagement with either end of the saw blade; while the jaw 8 is provided with similar lugs 35 and 36 for 20 engagement with the other end of this blade; and such engagements are effected at pleasure by placing one of the collar lugs and the corresponding jaw lug in the pinholes 37 and 38 respectively, which perforate the opposite 25 ends of the saw blade 40, and by turning inward the clamp screw 31, as shown in Fig. 8. The clamp thus places the saw blade in

tension; and the saw, when so united, has for handles the parts 9 and 14.

I claim as my invention—

1. A combination tool comprising a tubular casing having wrench jaws, a tubular handle separable from the casing, a separable blade adjustable in these tubular members, means including a spring-mounted pin 30 for uniting the blade with the casing, and like means for uniting the blade with the handle in different positions of mutual adjustment.

2. A combination tool comprising a tubular casing with pivotally adjustable jaws, a tubular handle separable from the casing, a separable blade adjustable in these tubular members, means including an adjustable block 35 for holding the pivoted jaws in different positions of adjustment, means including a spring-mounted pin 40 for uniting the blade with the casing, and like means 45 rigidly uniting the blade with the handle in different positions.

Witness my signature at Omaha, Nebraska,
July 29, 1926.

STEPHEN PETERS.
